ROAD FORM JOINT

Ottwin L. Braun, Pittsburgh, Pa., assignor to Reliance Steel Products Company, McKeesport, Pa., a corporation of Pennsylvania

Application April 2, 1947, Serial No. 738,871

3 Claims. (Cl. 25—118)

1

This invention relates to a road form such as is used in the construction of concrete roads for defining the sides of the road and the elevation of the road surface. More particularly, my invention concerns a road form joint whereby the ends of adjoining rails or forms may be securely fastened together in end-to-end relationship and rigidly secured in alinement.

I provide a sliding member located at one end of a rail and which closely fits against the base, the web and the inside of the rail head. The member has a projection which in rail locking position bears against abutments, one of which is secured to the rail base of one rail, and another abutment which is fastened to the rail base of an adjoining rail.

One object of my invention is to provide a retainer member which is slidable to engage two end portions of adjoining rails and hold them securely in end-to-end alinement, and which member can be moved readily so as to free the end of one of the rails.

Another object is to provide an end joint which will reinforce the ends of abutting rails.

A further object is to provide means for simultaneously clamping adjoining rails so that the binding members are tightly urged against the rail ends.

The present preferred embodiment of my invention is illustrated in the accompanying drawings wherein:

Figure 1 is a view in section along the line I—I of Figure 2 of a rail joint securing together the ends of two abutting end-to-end rails which are shown in dotted lines;

Figure 2 is a vertical section on the line II—II of Figure 4;

Figure 3 is a plan view of a retainer plate or sliding member used in my invention; and

Figure 4 is a view in elevation of a joint in which my invention is used.

The road rails or road forms which are commonly employed as side forms in concrete road construction are bent from sheet metal of suitable gauge. Each rail has a base or base flange 10 which rests on the ground surface, a web 11 upstanding from the base, and a tread flange 12 with a depending lip 13. The rails are laid end-to-end and securely fastened together by my joint structure. The road making material is placed between the parallel rails which define the road edges, while the tread or top 12 of the rail is used to establish the grade of the road surface. The rails not only define the road edges and the road surface level, but are usually em-

2

ployed to support heavy road laying and finishing equipment. As a consequence the rails are subjected to heavy strains.

The rails must be fastened to each other at their ends in a rigid manner so that a low joint with a consequent unevenness in the road surface may be avoided. My rail joint does this in a satisfactory and novel manner.

The joint includes a sliding member or retainer plate 14, which is slidable in the rail, and as shown, is slidable in the adjacent end portion of an adjoining alined rail to maintain said rails in alinement end-to-end. The member has a vertical cross section which resembles the numeral 7 (see Figure 2), the upright portion 15 lies along the web for its full depth, and the cross portion 16 lies in close contact with the under side of the tread 12 of the rail. The bottom of the upright portion fits closely against the rail base. The member may slide along the rail but cannot move vertically. The ends of the slide has inwardly turned portions or ears 17 which do not extend the full depth of the upright 15 (see Figure 2). The ends of the cross portion 16 are trimmed as shown in Figure 3. In order to prevent battering of the side ears 17, I weld to each of the ears a driving extension 18.

Secured to the slide or joining plate 14 between the ears 17 is a jamming or force-transmitting member 19 which comprises a metal angle, the legs of which are welded to the upright 15. The outer edge or corner of the angle provides a narrow line-like surface which is parallel to and spaced from the face of the upright 15, and is parallel to and spaced from the base flange 10. The angle 19 also serves to stiffen the retainer plate 14 in a longitudinal direction.

At each end of each rail a springable member 21 is secured. The member consists of a rectangular piece of metal having a stake receiving hole 22 therein registering with a corresponding hole in the base of the rail. Near the inner end of the member 21 an upstanding lug 20 having outwardly flaring ends 23 is welded. The member 21 is welded along its outer end and for about $\frac{1}{3}$ of its length to the rail base. The lug 20 is so located with reference to the rail that the inner end of member 21 springs a little from the rail base when the angle member 19 is driven into the engaging position with the lug 20 as shown in Figure 4—the position where two rails are joined. The plate 14 is securely locked in rail jointing position by its close fit with the rail and tight engagement of the angle 19 and the lug 20. The corner of the angle 19 which en-

gages the spring plates 20 provides a narrow line-like engaging surface which is movable rectilinearly over the surface of the spring plates as the retainer plate is slid along the web 11.

When it is desired to disjoint the rails, the member 14 is driven back out of engagement with the lug 20 of the adjoining member and back of the end of the rail. The member becomes operative when the rails are laid end-to-end and the slide 14 forced into engagement with the lug 20 10 of the adjoining rail as shown in Figure 4.

The rail joint is quite stiff, as the locking member is tightly jammed into intimate contact with the rail end, so that no low joints will result when the commonly encumbered loads are imposed on the rails during construction.

I have described the presently preferred embodiment of my invention, but it is to be understood that various changes may be made therein and the invention otherwise embodied within the scope of the following claims.

I claim:

1. A joint for road rail forms having spaced parallel base and tread flanges with a vertical web therebetween which comprises a joining plate abutting against said web and extending from said base to said tread flanges so that said flanges confine movement of said plate to a sliding movement along said web in a horizontal direction, and means resiliently maintaining said plate abutting against said web comprising a spring plate connected to and projecting upwardly from said base flange but being spaced from said web a distance greater than the thickness of said joining plate, and a force-transmitting member connected to said joining plate and having a narrow line-like surface movable recti-

linearly over the surface of said spring plate upon sliding movement of said joining plate along said web, said narrow line-like surface being spaced from said base flange, and said joining plate and force-transmitting member having an overall thickness greater than the spacing of said spring plate from said web so that said spring plate will be resiliently deflected away from said web when the joining plate is slid to an operative position between the joining and deflecting plates with said surface engaged with said spring plate, the resilience of said spring plate upon deflection thereof reacting against said force-transmitting member to hold said joining plate tightly against said web.

2. A joint as claimed in claim 1 wherein said force-transmitting member comprises an angle section having angularly extending flanges connected along their outer edges to said joining plate, and a common inner edge providing said narrow line-like surface.

3. A joint as claimed in claim 1 wherein the spring plate has vertically extending lateral edges which are curved in a direction away from said web to facilitate sliding movement of said joining plate to a position between said spring plate and web and to facilitate deflection of said spring plate by said force-transmitting member.
